James Heine Inventor,

By Atty

J. C. Clayton & Co.

United States Patent Office.

LOUIS HEINE, OF PHILADELPHIA, PENNSYLVANIA.

Letters Patent No. 78,971, dated June 16, 1868; antedated June 13, 1868.

IMPROVEMENT IN STEAM-BATHS.

The Schedule referred to in these Letters Patent and making part of the same.

TO ALL WHOM IT MAY CONCERN:

Be it known that I, LOUIS HEINE, of Philadelphia, in the county of Philadelphia, and in the State of Pennsylvania, have invented a new and useful Steam-Bed for treating invalids; and I do hereby declare that the following is a full, clear, and exact description thereof, reference being had to the accompanying drawings, and to the letters of reference marked thereon, in which—

Figure 1 is a longitudinal section through the invention.

Figure 2 is a plan view.

The nature of my invention consists in the combination of a gauze double-bottom bed, with a steam-tight frame as a bedstead, and an air-tight cover, for steaming invalids with steam from herbs, as herein more fully described.

To enable others skilled in the art to make and use my invention, I will describe its construction and operation.

In the construction of my invention, in fig. 1, A is the bedstead or steam-box, which is composed of four posts, having sides and ends of boards, and with a close bottom, thus forming a complete box, without a cover.

B, in fig. 1, is a perforated cylinder, attached at one end to a steam-pipe, which passes through the head of the box, and the other end rests, by means of a bearing, on a cleat, to allow the cylinder to revolve.

C is the sacking-bottom, on which to lay the patient or the invalid.

D is a gauze bottom, attached to the same frame with D, and this frame, or double frame, is fitted to the box A, so as to be easily set into and taken out of the box A, and rests on cleats, at a proper distance above the cylinder B.

The frame D is made parallel to the bottom, while the frame C is slightly inclined, being raised at the head end, to give ease in lying on the same, and is placed some distance above the frame D. It may be six inches, more or less, as the case may require.

D', the pillow, made in shape to suit the reclining position of the invalid.

f f are holes in the cylinder B.

b, the thermometer, of any ordinary description.

E, the cover, of oil-cloth, for spreading over the patient when in the process of steaming, which is fastened to the box by tacks e e in fig. 2.

a a are pins or buttons, to which the cover is attached.

d is an opening, to allow the mouth and nose of the patient to be uncovered and exposed to the atmosphere.

e e e are button-holes and buttons, to enlarge the aperture, if required.

In the operation of my invention, the patient or invalid is laid on the couch or bed C, with the head resting on pillow D'. The herbs to be used are placed, with water, in a vessel, to be heated in any ordinary manner, and attached, in any convenient manner, to the pipe of cylinder B, escaping through the holes f, in said cylinder, into the box or frame of the bed A. The thermometer b will give the degree of heat required in each case for each patient or invalid. The steam will pass through the gauze bottom D regularly, and be diffused through the space between it and the bottom or bed C on which the patient is lying, and is brought directly in contact with the patient, who has the cover E drawn over the person, and buttoned down tightly, by means of the buttons a a, thus completely surrounding the patient in steam of herbs.

When the patient is sufficiently steamed, he is taken off the bed, and rubbed dry with coarse towels, wrapped in fresh blankets, and then placed on a lounge.

In placing the invalid to be steamed on the bed C, he or she is wrapped in blankets, and is kept under the operation, say about from five to ten minutes, or until a complete perspiration is produced, and the invalid is thoroughly heated by steam from various herbs, thus effecting a change in the system of the patient generally in ten minutes.

It is well known that many diseases will yield to steam containing the extract of herbs, when properly selected and applied, which I do properly apply by means of my invention.

I may find it convenient to attach a valve to the pipe leading into the cylinder B, to regulate the flow of steam to the patient.

Having thus described the nature of my invention, what I claim as new, is—

The frame or bedstead A A, in combination with the gauze bottoms C and D, cylinder B, and cover E, constructed substantially as described, operating as and for the purposes set forth.

In testimony that I claim the above-described invention, I have hereunto signed my name, this 13th day of November, 1867.

LOUIS HEINE.

Witnesses:

GEORGE HEINE,
Jo. C. CLAYTON.
